UNITED STATES PATENT OFFICE

JOHN H. BROUSSEAU, OF NEW YORK, N. Y.

GARTER

Application filed February 15, 1930. Serial No. 428,639.

My invention relates to the class of devices commonly used to support a stocking or sock, and an object of my invention, among others, is the production of a garter, 5 that may be adapted to hold a stocking or a sock by extending the garter its full length and attaching its upper end to an article of wearing apparel, or by wrapping it around the leg.

10 One form of a garter embodying my invention, and in the construction and use of which the objects herein set out, as well as others, may be attained, is illustrated in the accompanying drawings, in which—

15 Figure 1 is a face view of a garter embodying my invention.

Figure 2 is a view in section, scale enlarged, with the central portion broken away and on the dotted line 2—2 of Figure 1.

20 Figure 3 is a view on reduced scale illustrating different ways of using the garter in its extended form, as for holding a stocking.

25 Figure 4 is a similar view illustrating the use of the garter by wrapping it around the leg to support a sock.

Figure 5 is a view, scale enlarged, as compared with Figures 3 and 4, showing a manner of use with a stud inserted through an eyelet and engaged by a loop.

30 In the accompanying drawings the numeral 5 indicates a strap comprising the body of my improved garter and that may be formed of knitted or woven fabric or similar material. This strap has a loop 6 secured at one end, through which loop the end of the strap may be passed, which end may be secured to the strap as by means of a buckle 7, of ordinary construction. The loop also is formed with an eye 8 and a clasp 9 is pivotally mounted on the eye. This clasp is of the ordinary form common to structures of this class and embodies a 35 key hole opening comprising the tapered portion 10 and the enlarged part 11, the latter adapted to receive the head of a stud 12 secured at the end of a tab 13, which tab is also secured to and depends from the eye 8. As before remarked, the clasp 9 and tab

and stud are of ordinary form and construction, but the device as a whole is new in that it embodies the eye 8 at the end of the clasp.

40 A pad 14 preferably of fabric is secured at the end of the strap 5 opposite the loop 6, and an eye 15 preferably of metal is mounted in said pad. A clasp 16 similar to the clasp 9 is pivotally mounted on the eye 15 and cooperates with a tab 17 having a stud 18 in the same manner as that of the tab 13 and clasp 9.

45 The holes 19 of the eyes 8 and 15 are of such size that the studs 12 or 18 may be passed into said holes and be held therein by a clasp 9 or 16 appurtenant to the stud inserted through a hole.

50 The pivotal connection herein described enables the strap or body 5 to be located at an angle to the clasp projecting from its end, and this permits the garter to be wrapped around the leg, as shown in Fig. 4, the end of the garter opposite to that secured to the sock 20 being attached to the clasp 16 by inserting the stud 12 through the hole in the eye 15.

55 The garter may be used in its extended form, and as shown in Figure 3, by attaching either end in an ordinary manner to a stocking 21, and by attaching the opposite end of the garter in the same manner to an article 22 of wearing apparel. As an alternative manner of use, an eyelet 23 may be fixed in an article of wearing apparel, as a corset 24, and one of the studs 12 or 18 60 may be inserted through such eyelet and engaged by a clasp 9 or 16 as shown in Figure 3, the engagement of the stud and clasp in this latter instance being the same as hereinbefore described with respect to the manner of use.

65 In accordance with the provisions of the patent statutes, I have described the principles of operation of my invention together with the device which I now consider to represent the best embodiment thereof; but I desire to have it understood that the device shown is only illustrative, and that the invention may be carried out by other 70 means.

means and applied to uses other than those above set out.

I claim—

- 5 1. A garter comprising a strap, a garment clasp at each end of the strap, each clasp including a garment securing member and means for directly attaching one of said clasps to the clasp at the opposite end of the strap by the use of said garment securing member.
- 10 2. A garter comprising a strap, a garment clasp at each end of the strap, each clasp comprising a keyhole slot and a stud to engage said slot, and means for pivotally attaching one of said clasps to the strap to swing in a plane parallel with the plane of the face of the strap.
- 15 3. A garter comprising a strap, a garment clasp at each end of the strap, each clasp comprising a key-hole slot and an engaging stud therefor, a tab carrying stud having an eye extending therethrough, and a tab secured by said stud, said eye being adapted to receive the stud from the opposite end
- 20 25 of the strap.

JOHN H. BROUSSEAU.
